(57) **CLAIM**

An ornamental design for a battery for camcoder, as shown and described.

DESCRIPTION

FIG. 1 is a rear perspective view of a battery for camcoder;
FIG. 2 is a front perspective view thereof;
FIG. 3 is a front view thereof;
FIG. 4 is a rear view thereof;
FIG. 5 is bottom view thereof;
FIG. 6 is a top plan view thereof;
FIG. 7 is a left side view thereof; and,
FIG. 8 is a right side view thereof.
